INDICATOR CARD FOR ANNUNCIATORS
AND THE LIKERobert S. Edwards, New Rochelle, N. Y., assignor
to Edwards and Company, Inc., a corporation
of New York

Application January 7, 1932, Serial No. 585,255

4 Claims. (Cl. 281—43)

This invention relates to indicating means and the method of producing the same.

One of the objects of this invention is to provide a simple, inexpensive, and practical identifying card and holder therefor that will be well adapted to meet the varying conditions of hard practical use. Another object is to provide a simple and dependable arrangement for holding a card bearing identifying indicia in position such as, for example, on the drops of an electric or other annunciator. Another object is to provide a simple, inexpensive, and thoroughly practical method of making cards bearing identifying indicia. Another object is to provide an inexpensive and convenient supply of indicating cards well adapted to meet the widely varying requirements of practical use. Another object is to provide devices of the above-mentioned character that will make for great saving in time in production, shipping, and handling, as well as in assembly. Other objects will be in part obvious or in part pointed out hereinafter.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the accompanying drawing in which are shown several of the various possible embodiments of the mechanical features of my invention,

Figure 1 is a perspective view of an indicator card related to its holder;

Figure 2 is a similar view of a possible modified form;

Figure 3 is a plan view on a smaller scale, of a sheet of cards showing the latter in one stage of my process, and

Figure 4 is a view similar to that of Figure 3 but showing a modified form.

Similar reference characters refer to similar parts throughout the several views of the drawing.

As conducive to a clearer understanding of certain features of my invention, it might here be pointed out that in practice, particularly in annunciators, there is a need for a relatively great variety of designation or identifying indicia and that, in accordance with practice heretofore known, the supply and mounting of appropriate cards that bear the requisite indicia has been fraught with difficulty and annoyance both

in the provision and mounting thereof in place as well as in the handling and commercial shipping thereof. Also, the mounting of cards bearing indicia or designations according to prior practice, has been cumbersome, crude, and insecure. One of the dominant aims of this invention is to eliminate, in a thoroughly dependable, efficient, and inexpensive way, such difficulties as those above-mentioned, and to greatly facilitate the manufacture, supply, handling, and mounting of such cards.

Referring now to the drawing and more particularly to Figure 1, I have shown a card holder generally indicated at 10 which, in accordance with certain features of my invention, is preferably made of sheet metal, having a back portion 11 of a generally quadrangular or rectangular shape and provided with upper and lower bent-over flanges 12 and 13 which may be integrally formed with the part 11 and which are thus made to provide two parallel horizontally extending grooves or slots or ways. Illustratively, the device 10 may be considered to be part of an annunciator, such as the so-called "drop" thereof adapted to be moved by any suitable mechanism from a position where it is invisible to a position where it becomes visible so as to display a suitable designation or identifying indicia; in such case it may be provided with wings, one of which is shown at 14 adapted to be pivoted as at 15 so as to be swung from one of the above-mentioned positions to the other. Inasmuch as the means for moving the device 10 are not per se part of my invention they are not shown or described but may take any suitable form.

In practice an annunciator may have any number of such "drops" to identify any one of a corresponding number of points from which a signal initiates. These designations may be numerical and in Figure 1 the numeral "1" may be considered illustrative. These designations, however, may also include a large variety of words, such as "Maid", "Valet", "Butler", "Front door", "Rear door", "Master bedroom", "Cashier", "Boy", "Teller", "President", depending upon the use to which the particular annunciator and the number of drops therein are put.

To meet the widely varying requirements of practical use, in this particular respect, has in practice been an expensive and troublesome procedure, but in accordance with certain features of my invention, I dependably eliminate such difficulties.

Turning now to Figure 4, I first provide a sheet generally indicated at 16 of a suitable material

which may be of a suitable cardboard. This sheet is preferably rectangular in shape and on it I print, in regularly aligned vertical and horizontal rows all of the more usual identifying designations met with in practice.

In Figure 4 there are shown nine horizontal rows and ten vertical rows of designations of which only a few are actually reproduced in Figure 4, the rest being indicated by the indicated 10 rectangles, and with this illustrative arrangement of nine horizontal rows and ten vertical rows, I am enabled to print on a single sheet 15 ninety different designations of which those above-mentioned may be considered illustrative or typical. Preferably these designations are 20 different, though I may duplicate such of those as are met with more frequently in practice.

The printing may be achieved in a single operation inasmuch as the designations, thus aligned 25 horizontally and vertically, are easy to set up in type or are easily formed into a single printing plate. The printing may be in any desired colors or the designations may be printed in black on a white background or vice versa.

Some of the spaces may be left blank so that 30 the ultimate user may print or letter or apply his own designation or identifying indicia; in case the user's requirement is of such an unusual character as not to be met by any of the actually 35 printed designations. For such purpose I may print or provide rectangular spaces in place of the designation so as to provide an accurate guide within which the user may apply his own indicia; in Figure 4 I have shown two rectangular spaces 40 17 and 18 provided each with two rectangular outlined blank spaces 17^a, 17^b and 18^a, 18^b, respectively, as illustrative of how I provide for this contingency.

After the printing has been completed, I cut the 45 sheet 16 along the lines indicated at 19, 20, 21, 22, 23, 24, 25, 26 and 27, thus physically to sever the vertical rows of rectangularly shaped spaces from each other but it is to be noted that these lines of cutting 19, 20, 21, etc., terminate well within the 50 upper and lower parallel horizontal edges of the sheet 16, thus to provide upper and lower margins 16^a and 16^b which hold the vertical rows together. Where there are ten vertical rows of printed designations, I therefore provide nine lines of severance or cutting 19-27 inclusive.

I then score or perforate the sheet 16 along 55 horizontally parallel lines vertically spaced; these lines of scoring or perforation are shown in Figure 4 at 28, 29, 30, 31, 32, 33, 34, 35, 36 and 37. These lines of perforation extend from edge to 60 edge of the sheet, as is clearly indicated in Figure 4, and they are made along the boundary lines of the nine horizontal rows of printed identifying indications. They thus not only mark and identify the upper and lower boundaries of these 65 horizontal rows but they also prepare the individual vertical rows for segregation crosswise thereof and into individual rectangular cards, each bearing indicia as above outlined. The uppermost and lowermost lines of scoring or perforation shown at 28 and 37 likewise prepare the 70 vertical rows for easy manual severance from the upper and lower marginal strips 16^a and 16^b of the sheet 16.

Such a sheet is virtually all-inclusive of the 75 needs met with in practice, is simple and inexpensive to produce, and is easily furnished, handled, or shipped to the user of such designating cards or indicia, for example, a user of a multi-drop annunciator. The sheet may be folded along

any one or more lines of perforations or along one or more lines of cutting, and thus lends itself to easy and compact packing or shipping but when unfolded, as when received by the user, the latter simply breaks or tears out of any vertical row the particular card or cards that he wishes to mount on the card holders, such as the holders on the annunciator drops, it being here noted that, instead of having to delve through a large number of individual cards (ninety, for example) all of 10 the cards are before him in sheet form and it is a simple and speedy matter to select the particular designation or designations required.

Now with respect to any given type of holder, such as the holder 10, the lines of cutting and the 15 lines of perforation or scoring of the sheet 16 of Figure 4 are so spaced that they outline individual cards whose horizontal dimension matches the horizontal dimension of the holder 10 of Figure 1 while the vertical dimension of the individual 20 cards just about matches the vertical spacing between the bottoms of the grooves or ways provided by the flanges 12 and 13; thus, when any individual card, referring now to Figure 4, for example the card 38 bearing the identifying 25 indicia "1", already severed along its vertical side edges 38^a and 38^b, is manually torn out along the perforations of its upper and lower horizontal edges 38^c and 38^d, it is ready for insertion into the holder 10.

But the separation of the card 38 from its vertical row as above described leaves the upper and lower edges 38^c and 38^d virtually serrated, as is better shown in Figure 1 in which the upper serrated edge 38^c is shown in perspective.

The card 38 is then slid in a horizontal direction as viewed in Figure 1 into the grooves or ways provided by the flanges 12 and 13 whereupon the serrated upper and lower edges of the card 38, because of their serrated and frazzled 40 fibrous character, yieldingly but with secure friction engage or bottom in the grooves or ways to hold the card 38 from horizontal displacement. Moreover, the flanges 12 and 13 conceal the torn or serrated upper and lower edges while the clean-cut sides edges 38^a and 38^b become aligned with the side boundaries of the back plate 11, presenting a neat appearance.

The character of the upper and lower edges 38^c and 38^d and their coaction with the grooves 50 or ways in which they are received are important for I am enabled to achieve many thoroughly practical advantages thereby; for example, if these edges were cut, and assuming that they initially were snugly received and fitted within 55 the grooves or ways of the flanges 12-13, a subsequent even slight shrinkage of the paper or cardboard of the card 38 leaves the latter in a loosened condition in the holder from which it, under the vibration and movement to which the 60 holder is subjected in practice, could easily slide out. But the fibrous and serrated character of the edges that I provide according to certain features of my invention insures a sufficient range of yieldability as well as a greater area of contact 65 with the metal holding parts as to prevent such actions as just described from taking place.

Where, under certain practical conditions, the card holder is provided with grooves, slots, or ways that extend vertically, such as in the holder 42 70 of Figure 2, in which the sheet metal flanges 43 and 44 extend vertically instead of horizontally as do the flanges 12 and 13 of Figure 1, I provide a sheet 45 shown in Figure 3, made up in substantially the same steps as those outlined above 75

in connection with Figure 4 excepting that the lines of scoring or perforations, shown in Figure 3 at 46, extend vertically between the upper and lower edges, while the lines of severance or cutting indicated at 47 in Figure 3 extend horizontally and terminate short of the two side edges of the sheet 45, thus to provide marginal portions 45^a and 45^b which hold the horizontally severed rows of cards or designations together.

10 To mount a card in the holder 42 of Figure 2, such as the card 48 of Figure 3, the card is torn along the perforated side edges 48^a and 48^b thereof, thus not only freeing the card from the sheet 45 but also giving its two side edges 48^a and 48^b 15 the serrated fibrous and frazzled character above described in connection with the upper and lower edges 38^c and 38^d of the card 38 of Figures 1 and 4.

The card 48 is then inserted into the holder 42, 20 its upper and lower cut edges presenting a neat appearance while its serrated side edges are not only hidden in back of the flanges 43 and 44 (Figure 2) but also coact with the bottom walls of the grooves or ways as will now be clear in view of what has above been set forth.

25 Insofar as certain features of my invention are concerned, the sheet of which the cards are made may be of any other material, for example, like celluloid, the serrations of the edges being thus individually yieldable.

30 It will thus be seen that there has been provided in this invention an identifying card assembly and method of achieving the same in which the various objects hereinabove set forth, together with many thoroughly practical advantages, are successfully achieved, and the many disadvantages and difficulties of prior practices successfully eliminated.

35 As many possible embodiments may be made of the mechanical features of the above invention and as the art herein described might be varied in various parts, all without departing from the scope of the invention, it is to be understood that all matter hereinabove set forth or shown in the accompanying drawing is to be interpreted as illustrative and not in a limiting sense.

I claim:

40 1. A sheet of connected cards bearing appropriate indicia; the said cards being individually

intended to be supported between opposed flanges of sheet metal holders for annunciators and the like, said sheet being cut through in one direction in parallel lines terminating short of two opposed edges of the sheet and the spacing of said parallel lines being substantially equivalent to the length of the flanged edges of said sheet metal holders, and being scored along parallel lines extending crosswise of the cuts and between the remaining two opposed edges of the sheet, 10 the spacing between the parallel lines of scoring being substantially equivalent to the spacing between the inner portions of the opposed flanges of said holders, said lines of cut and lines of scoring sub-dividing the sheet into quadrangles 15 within which the respective indicia are centered, whereby, when any one card is separated and removed from said sheet by tearing along the lines of scoring, the torn scored edges of the card provide yieldable fibrous edges for yielding frictional engagement with the said flanges of said holder.

2. An indicator card for insertion into an indicating card holder that has two opposed grooves into which a card may be slid, comprising, in 25 combination, a card made of cardboard and having serrated and torn edge portions, thereby made yieldable, and each adapted to be received in one of the grooves of the card holder.

3. An indicator card for insertion into an indicating card holder that has two opposed grooves into which a card may be slid, comprising, in combination, a card having a relatively stiff main body portion and two opposed substantially parallel edge portions, each adapted to be received in one of said grooves of the holder, one of said edge portions of the card being yieldable for yieldable engagement in its groove.

4. An indicator card for insertion into an indicating card holder that has two opposed grooves 40 into which a card may be slid, comprising, in combination, a card having a relatively stiff main body portion and two opposed substantially parallel edge portions, each adapted to be received in one of said grooves of the holder, and each edge 45 portion being serrated whereby the serrations thereof effect a yieldable wedging of the card between said two grooves.

ROBERT S. EDWARDS.
